STITCH AND WORK HOLDER FOR KNITTING NEEDLES

Alice T. Wong, Honolulu, Territory of Hawaii

Application February 28, 1938, Serial No. 193,140

3 Claims. (Cl. 66—117)

This invention relates to knitting needles, and its general object is to provide a stitch and work holder, that is primarily designed for knitting needles particularly of the double point tubular work type, for connection to the points thereof to hold stitches to prevent dropping thereof when the needle is not in use, or for cooperation with the needle or alone, for receiving a portion of the work or the entire work thereon for trying 5 on the work, such as a skirt or the like, upon a model for fitting purposes, from time to time as the work progresses so that a proper fit will be assured when the work is completed.

A further object is to provide a combined needle 15 and stitch or work holder in which the latter can be easily and expeditiously connected and disconnected with respect to the needle points, and the holder is simple in construction, inexpensive to manufacture, and extremely efficient in use and service.

This invention also consists in certain other 20 features of construction and in the combination and arrangement of the several parts, to be hereinafter fully described, illustrated in the accompanying drawing and specifically pointed out in the appended claims.

In describing the invention in detail, reference 25 will be had to the accompanying drawing wherein like characters denote like or corresponding parts throughout the several views, and in which:

Figure 1 is a view of a tubular work knitting needle having openings in the points thereof to receive and connect the stitch and work holder which forms the major part of the present invention.

Figure 2 is a view partly in section illustrating a 30 stitch holder applied to the needle points.

Figure 3 is an elevation illustrating the application of a holder to a needle point.

Figure 4 is a view of the work holder.

Referring to the drawing in detail, and particularly to Figure 1, it will be noted that the needle of that figure is of the usual double point tubular work type, and which includes a flexible body 1 having formed on or otherwise secured to the ends thereof needle shanks 2 that terminate at their free ends in knitting points 3 which in the present instance have openings 4 extending transversely therethrough in close proximity to the extreme outer ends thereof.

While the stitch holder as shown in Figure 2 and the work holder in Figure 4 are of the same structure, the stitch holder is much shorter than the work holder, and both the stitch holder and work holder include a resilient strand-like or

coil spring body 5 that has formed on or otherwise secured to the ends thereof shanks 6, which terminate in looped ends to provide hooks 7.

The hooks 7 have their free ends outwardly flared as at 8 and the outwardly flared portions 5 engage the shanks 6 at the juncture of the hooks thereof, as clearly shown in Figures 2 and 4, so that the hooks are normally closed, but due to the inherent resiliency thereof, it will be obvious that they can be readily opened, for application 10 to the knitting points, by being passed through the openings 4, as best shown in Figure 2, or in hooked association with each other as shown in Figure 4.

While it has been stated that the short form 15 of the holder of Figure 2, is primarily designed for holding stitches to prevent dropping thereof, it will be obvious that a great number of stitches may be transferred from the needle to the holder, due to the length of the latter, but the long form 20 of Figure 4 is primarily designed to act in the capacity as a work holder and is of sufficient length so that all the work can be transferred from the needle thereto, for use in trying the work on a model for fitting purposes, as previously 25 set forth.

While I have illustrated my stitch and work holder as being applied to a needle of the double point tubular work type, it of course can be used in a straight needle to prevent dropping of a 30 stitch, and in that event the knitting point is provided with an opening to receive the hook at one end of the holder, and the hook at the opposite end thereof, is then connected to the hook that is directly connected to the knitting point.

It is thought from the foregoing description that the advantages and novel features of the invention will be readily apparent.

It is to be understood that changes may be made in the construction and in the combination 40 and arrangement of the several parts, provided that such changes fall within the scope of the appended claims.

What I claim is:

1. In combination, a knitting needle having an 45 opening in the knitting point thereof, and a stitch and work holder, and hook means on said holder to be received in the opening for securing the holder to the knitting point of the needle.

2. In combination, a knitting needle of the 50 double point tubular work type and each knitting point having an opening therein, and a stitch and work holder including a resilient strand like body, shanks formed on the ends of the strand like body, hooks on the free ends of the shanks and 55

receivable in the openings of the knitting points for securing the holder to the needle.

3. In combination, a knitting needle of the double point tubular work type, and each knitting point having an opening extending transversely therethrough in close proximity to the extreme

free end thereof, and a stitch and work holder including a coil spring body, shanks formed on the ends of the body, and normally closed hooks formed on the shanks to be received in the openings of the knitting points. 5
